DESIGN FOR A PIANO CASE

Fritz Huettemann, Cincinnati, Ohio, assignor to
The Baldwin Company, Cincinnati, Ohio

Application July 26, 1937, Serial No. 70,657

Term of patent 7 years

To all whom it may concern:

Be it known that I, Fritz Huettemann, a citizen of the United States, residing at Cincinnati, in the county of Hamilton and State of Ohio, have invented a new, original, and ornamental Design for a Piano Case, of which the following is a specification, reference being had to the accompanying drawing, forming part thereof.

I claim:

The ornamental design for a piano case, as shown.

FRITZ HUETTEMANN.
